ELECTRIC CURRENT RECTIFIER

Ernst Kobel, Ennetbaden, Switzerland, assignor
to Aktiengesellschaft Brown, Boveri & Cie.,
Baden, Switzerland, a joint-stock company of
Switzerland

Application May 28, 1931, Serial No. 540,665, and
in Germany June 6, 1930

6 Claims. (Cl. 175—363)

This invention relates to improvements in electric power rectifiers of the metallic vapor arc type in which the vapor and the arc are inclosed within a metallic tank.

5 An electric power rectifier of the character described must be cooled and the inclosing tank is therefore made double-walled to permit the circulation of a cooling medium therethrough. The interior surfaces of the tank thus provide cooled 10 surfaces on which a portion of the metallic vapor condenses and returns to the cathode which is usually mercury. In the normal operation of such rectifiers, the cooling surfaces however take on a potential which is positive, by several volts, 15 relative to the cathode. The positive mercury ions are repelled from the cooled surfaces of the tank and the cooled surfaces of a cooling coil, generally arranged within the tank, by the positive charges thereon which exert an electrical 20 damping on the natural movement of the ions resulting from their temperature. Clouds of ions thus checked hinder the flow of the neutral mercury molecules so that the transmission of heat from the vapor to the condensation surfaces is 25 retarded. The reunion of the ions with the molecules also prevents condensation of the ions as long as the same are electrically charged. Both of the above disadvantages may be avoided if the 30 surfaces on which the vapor is to be condensed are charged negatively relative to the cathode.

It is, therefore, among the objects of the present invention to provide an electric power rectifier of the metallic vapor arc metal inclosed type with means for preventing the formation of a 35 layer of ions adjacent but out of contact with the cooled surfaces of the inclosing tank.

Another object of the invention is to provide an electric power rectifier of the metallic vapor arc metal inclosed type in which the inclosing 40 tank is cooled and the cooled surfaces thereof are charged negatively with respect to the cathode.

Objects and advantage, other than those above set forth, will be apparent from the following description when read in connection with the accompanying drawing which somewhat diagrammatically illustrates one embodiment of the present invention.

Referring more particularly to the drawing by characters of reference, the reference numeral 1 50 designates a double-walled metallic tank having a cathode well 2 formed in the bottom thereof to retain a vaporizable cathode material 3 which is preferably mercury. A double-walled extension 4 projects from the cover of the tank in communication with the interior thereof and forms a con-

denser chamber or dome for the metallic vapor. A plurality of anodes 6 extend through the tank and are insulated therefrom by bushings 7. Both the anodes and the bushings are sealed in gas-tight relation into the tank walls 60 through which they extend. The anodes are each provided with arc guides 8 as is usual in electric power rectifiers of the metal tank inclosed type.

A cooling coil 11 is arranged within the tank 1 and is supplied with a cooling fluid from a suitable source through an inlet 12 and the cooling fluid discharges from the coil through an outlet 13. Both the inlet and the outlet to the cooling coil pass through the tank walls through insulators 14 sealed in gas-tight relation therewith. 70 Although the cooling coil has been shown as cylindrical and substantially centered within the rectifier, it will be understood that it may be shaped differently and may also be arranged in different positions within the tank.

A suitable source of potential, such as a battery 16, is shown as being connected with the coil 11 at the point 20 and as being connected with a conductor 17 leading from the cathode 3. Potential may be continuously applied to the coil or 80 the potential may be controlled by a switch 18. The switch may be controlled manually or, as shown, may be connected across a shunt 19 with the conductor 17 in such manner that a closing coil 21 closes the switch when the output of the 85 rectifier reaches a certain value. It will be apparent that the switch may also be controlled in response to voltage, vacuum, vapor pressure in the rectifier, temperature of the rectifier, or cooling water temperature in any way now known. The 90 value of the negative potential impressed on the coil may also be varied automatically in response to any suitable value.

The present invention thus provides means whereby the charging of the cooling surfaces 95 within a rectifier at a potential which is negative with respect to the cathode causes a flow of positive mercury ions to such surfaces. The path of the neutral molecules to such condensing surfaces is therefore cleared and the ionized vapor 100 rising from the cathode is carried along by the stream of ions and molecules thus reducing the vapor pressure within the rectifier. An electrical drop is produced in this manner in addition to the partial pressure drop within the tank so that 105 the flow of the vapor to the cooled walls is increased and the transfer of heat therefrom is facilitated.

Although but one embodiment of the present invention has been illustrated and described, it 110

will be apparent to those skilled in the art that various changes and modifications may be made therein without departing from the spirit of the invention or from the scope of the appended claims.

5 The invention claimed is:

1. In combination with an electric current rectifier comprising a casing, a plurality of anodes and a vaporizable cathode constituting arcing electrodes for the flow of electric current therebetween, of means arranged within said casing external to the path for flow of current between said anodes and cathode operable to condense material vaporized from said cathode, and means 10 for impressing upon the first said means electric potential negative with respect to the potential of said cathode.
2. In combination with an electric current rectifier comprising a casing, a plurality of anodes and a vaporizable cathode constituting arcing electrodes for the flow of current therebetween, of means having cooled surfaces arranged within said casing external to the path of flow of current between said anodes and cathode operable to condense material vaporized from said cathode, and means for impressing upon the first said means electric potential negative with respect to the potential of said cathode.
3. In combination with an electric current rectifier comprising a casing having cooled surfaces, a plurality of anodes and a vaporizable cathode constituting arcing electrodes for the flow of current therebetween, of means arranged within said casing external to the path of flow of current between said electrodes and electrically insulated from said casing operable to condense material vaporized from said cathode, and means for impressing upon the first said means an electrical potential negative with respect to the potential impressed upon the said cathode.
4. In combination with an electric current rectifier comprising a casing, a plurality of anodes and a vaporizable cathode constituting arcing

electrodes for the flow of current therebetween, of a coil forming a path for the circulation of a cooling fluid arranged within said casing external to the paths for the flow of current from said anodes to said cathode, the said coil being electrically insulated from said casing and being operable to condense material vaporized from said cathode, and means for impressing upon said coil an electrical potential negative with respect to the potentials impressed upon the said cathode.

85

5. In combination with an electric current rectifier comprising a casing having cooled surfaces, a plurality of anodes and a vaporizable cathode constituting arcing electrodes for the flow of current therebetween, of means arranged within said casing external to the path for flow of current between said electrodes and electrically insulated from said casing operable to condense material vaporized from said cathode, a source of electric current supply operable to impress a potential upon said means negative with respect to the potential of said cathode, and switch means operable to effect operative connection of said source of current supply with the first said means.

90

95

6. In combination with an electric current rectifier comprising a casing having cooled surfaces, a plurality of anodes and a vaporizable cathode constituting arcing electrodes for the flow of current therebetween, of means arranged within said casing external to the path for the flow of current between said electrodes and electrically insulated from said casing operable to condense material vaporized from said cathode, a source of electric current supply operable to impress a potential upon said means negative with respect to the potential of the said cathode, and switch means actuated responsive to and in dependence upon the magnitude of the current flowing between said electrodes for causing operative connection of said source of current supply with the first said means.
